(57) **CLAIM**

The ornamental design for a coating machine, as shown and described.

DESCRIPTION

FIG. 1 is a front view of a coating machine showing our new design;

FIG. 2 is a perspective front view thereof; and,
FIG. 3 is an alternative perspective front view thereof.
The broken lines shown in the figures illustrate environmental structure and form no part of the claimed design.**1 Claim, 3 Drawing Sheets**FIG. 1

FIG. 2

FIG. 3
